POLISHING MACHINES FOR WOOD PLATES AND THE LIKE

Max Schmidt, Karlsruhe, Baden, Germany, assignor to
Firma B. Raimann G.m.b.H., Freiburg, Breisgau,
Germany

Filed June 24, 1958, Ser. No. 744,091

Claims priority, application Germany July 1, 1957

7 Claims. (Cl. 15—102)

The present invention relates to polishing machines, and more particularly to machines, operating with buff wheels, for polishing of wood plates and similar products.

It is already known to employ machines for polishing the surfaces of wood plates in which the work piece is manually held against a buff consisting of textile material and is reciprocated by an operator while in contact with the rotating buff wheel. In certain other polishing machines of known construction, the buff wheel oscillates above a stationary work piece or blank. In a still further type of apparatus of this general character, large-surface rotary buff wheels are swingably mounted at two sides of a turret which alternately moves their large polishing surfaces into sliding contact with the stationary work piece. A drawback common to such known apparatus is in that they require constant supervision, manual feeding of the plates, and are not suited for polishing of plates having greatly differing dimensions.

An important object of the present invention is to provide a machine for polishing the surfaces of wood plates and like products which is fully automatic, and which may be utilized with plates of various sizes and thicknesses.

Another object of the invention is to provide a machine of the above described characteristics which is constructed with a view to subject each work piece to a series of polishing actions.

A further object of the invention is to provide a polishing machine for plates made of wood or another material which is so constructed that the polishing means perform more than one motion while in contact with the work piece.

A still further object of the invention is to provide a polishing machine of the above described character which is so constructed as to allow rapid and convenient interchange and adjustment of such component parts which are subjected to greatest wear and tear during the polishing operation.

An additional object of the invention is to provide in the polishing machine as above set forth means for automatically or manually supplying a polishing medium to the surfaces of polishing means or directly to the surface of a work piece.

The above and certain other objects of the invention are attained by the provision of a machine which comprises essentially at least one elongated driven roller formed of a plurality of coaxially disposed bundles of buff wheels, and a driven conveyor for moving the work pieces at a fixed speed into contact with the polishing roller or rollers.

By providing separate drive means for the polishing rollers and for the conveyor, a fully automatic mode of operation is attained, the novel machine requiring very little supervision and, due to the multiple adjustability of polishing rollers, may be utilized with plates of greatly differing thicknesses.

If more than one polishing roller is utilized, the roller axles are preferably disposed in parallelism above and transversely of the conveyor system which leads the work pieces into contact with the rollers, and the rollers are

2

preferably driven at different angular speeds. It is advisable to drive the rollers in such manner that the speed of the roller first to contact a work piece is less than the speed of the next adjacent roller, and so forth.

5 The rollers are installed in a housing, preferably in the shape of an inverted receptacle, and are adjustable with respect thereto. Means is provided for swingably supporting the roller axles in the housing and for facilitating rapid removal of the rollers, when desired. Still further, 10 the just described means permits the removal of one or more rollers from contact with the advancing work pieces, if the operator desires to utilize less than the total number of rollers for a polishing operation.

The housing itself is adjustable in directions toward 15 and away from the conveyed work pieces, and supports one or more pressing rollers, usually covered with felt or other suitable soft substance, the pressing rollers being rigidly or yieldably installed in the housing in such manner that they hold the work pieces while the latter are subjected to the polishing action of rotating buff rollers.

20 Each polishing roller is preferably driven by its own motor with the motors so installed that they can follow the displacements of housing and/or the polishing rollers.

The machine further comprises means for supplying a 25 polishing medium to the rollers or directly to the surfaces of work pieces. The delivery of polishing medium, preferably a fluid, may be caused by hand pressure over suitable lever mechanism or in a fully automatic way.

In addition to being movable toward and away from 30 the advancing work pieces, the polishing rollers may be so mounted that they perform axial movements in directions substantially transverse to direction of advancement of the work pieces. Thus, the movement of each roller may be a composite movement consisting of rotation about its own 35 axis and of transversely reciprocating motions with respect to the advancing work pieces.

The novel features which are considered as characteristic for the invention are set forth in particular in the appended claims. The invention itself, however, together 40 with additional objects and advantages thereof, will be best understood from the following description of a specific embodiment when read in connection with the accompanying drawing, in which:

Fig. 1 is side elevational view of the machine as seen 45 from line I—I of Fig. 2 in the direction of arrows, one side wall of the roller housing and of a gear casing being broken away for better illustration of component parts;

Fig. 2 is top plan view of the machine as seen from 50 line II—II in Fig. 1 in the direction of arrows, the cover plate of the housing being broken away; and

Fig. 2a is a partial top plan view showing a modified embodiment.

Referring now in greater detail to the drawing, the 55 polishing machine therein shown comprises a frame or base 1 mounting a band conveyor 3 provided with spaced followers or lugs 2. The conveyor travels over sprockets 2a, 2b and has its upper run disposed in a horizontal plane. Sprocket 2a is driven by an electric motor 4 over a suitable gearing indicated by reference numeral 5.

In the upper run of conveyor 3, followers 2 consecutively engage a series of work pieces or blanks 14, here shown as wood plates, which travel in the direction of arrows A when the motor 4 is in operation. Members 65 14 may be loaded onto conveyor 3 by a suitable automatic dispensing device (not shown) or by hand. Similarly, polished plates at the discharge (left-hand) end of conveyor 3 may be collected by an automatic apparatus of any known construction.

A box-shaped housing 6 is vertically adjustably installed above the upper run of conveyor 3. Its under-side is open, thus enabling buff rollers 11 to protrude

therebeneath into contact with the traveling work pieces 14. Housing 6 is adjustable in vertical directions by a hand wheel 7 which operates four worm drives 8 disposed at the four corners of member 6. Thus, drives 8 together with hand wheel 7 constitute four jacks, each of which comprises a threaded spindle 9 having its upper end rotatably connected to a bracket 6a fixed to the underside of housing 6 at one of the latter's four corners, the spindle extending through a tapped bore in the stationary casing 8b and carrying at its lower end a worm wheel 8a meshing with a worm shaft 8c extending transversely across and beneath the upper run of conveyor 3. Worm shafts 8c of the respective left- and right-hand worm drives 8 carry pulleys 8d (only one shown in phantom lines in Fig. 1), these pulleys being connected by a chain or belt 10 also shown in phantom lines in Fig. 1. Thus, shafts 8c may be driven in unison by means of hand wheel 7 in a manner to cause uniform vertical displacements of housing 6 toward or away from the upper run of conveyor 3, depending upon the direction in which the wheel 7 is rotated.

Two buff rollers 11, each consisting of a series of bundled coaxially disposed textile discs, are mounted on parallel axles 18, each of which has its ends rotatably received in a pair of arms 12, 12a. Arms 12, 12a are swingable about their shafts 13 to adjust the height of rollers 11 in dependency on the thickness of work pieces 14, or to move one or both rollers away from contact with the work pieces. Vertical movements of rollers 11 are entirely independent from vertical movements of housing 6, this being brought about by a pair of hand wheels 15 and two lifting jacks 16 carried by the machine base 1. Each jack 16 comprises a bevel gear 16a meshing with a second bevel gear 16b at the lower end of a tubular member 16c having a tapped bore for reception of a threaded spindle 17 whose upper end abuts against the bearing 22 at one end of a shaft 18. Spindles 17 being in non-rotating engagement with bearings 22, and tubular members 16c being rotatable in their cases 16d, any rotation of hand wheels 15 will cause vertical displacements of the spindles in internally threaded rotating members 16c whereby the upper end of a spindle 17, acting against the bearing 22 and thereover against shaft 18 of a buff wheel 11, lifts or lowers the latter depending upon the direction in which a hand wheel 15 rotates.

Shafts 13 are turnably mounted in bearings carried by the housing 6. Obviously, suitable cutouts (not shown) are provided to permit oscillation of axles 18 about the adjacent shaft 13 when the one or the other hand wheel 15 is operated.

Rollers 11 are driven by a pair of electric motors 19 over belts or chains 19a. Each motor 19 is rigidly mounted on a plate or support 21 with the latter pivotally connected to a stationary base plate 20. Thus, the motors are free to follow vertical displacements of buff rollers 11. As before mentioned, the left-hand roller 11 is preferably driven at a speed exceeding that of the right-hand roller which latter is the first to come into contact with a work piece 14 when the conveyor advances in the direction of arrows A. Of course, both rollers 11 may be driven by a single adjustably mounted motor over suitable reducing gearing to rotate each roller at a different speed.

Arms 12a not only are pivotable about but also in a plane passing through the axes of their supporting shafts 13 so as to be movable, together with bearings 22, away from contact with the ends of roller shafts 18. It will be noted that one side of housing 6 (at the bottom of Fig. 2) is formed with an extension to permit such lateral movements of arms 12a. By so mounting shafts 18, rollers 11 may be interchanged in a very simple and convenient manner by simply pivoting the arms 12a and bearings 22 about pins 13a in directions away from the ends of shafts 18.

Work pieces 14 are pressed against the upper run of

conveyor 3 by means of felt rollers 23 which are mounted at the underside of housing 6. These preferably but not necessarily spring-biased rollers 23 (springs not shown) become more important when the conveyor system 3 operates without followers 2.

A polishing medium is supplied to rollers 11 by tray-shaped dispensing devices 24 which are connected with hand actuatable levers 25 so that the latter may press the trays against the respective rollers 11 whenever necessary. Of course, the usually liquid polish may be discharged from trays or receptacles 24 automatically at certain intervals, if desired, either onto the rollers 11 or directly onto the work pieces 14.

In operation, followers 2 continuously entrain plates 14 into contact with buff rollers 11 each of which is rotated at a different speed. The velocity of conveyor 3 and the number and pressure of rollers 11 are so selected that the upper surfaces of plates 14, retained in desired position by felt coated rollers 23 while passing beneath housing 6, are fully polished when the work pieces emerge at the left-hand side of the housing. The height of rollers 23 together with the housing 6 is adjusted by hand wheel 7, hand wheels 15 on the other hand allowing independent adjustments of rollers 11 with respect to the housing and work pieces 14. Motors 19 follow the displacements of rollers 11, for example, by their own weight when the rollers are moved in downward direction, and by the tension of belts 19a when one or both hand wheels 15 are rotated in directions to cause movements of one or both rollers 11 in opposing directions away from the upper run of conveyor 3.

It will be understood that a single roller 11 or more than two rollers may be utilized, and that the dimensions of members 11 and of conveyor system 3 will be so selected that the machine may accommodate plates of greatly differing dimensions. Also, and as above pointed out, one of the rollers may be moved away from the contact with advancing work pieces. It is equally within the scope of my invention to provide for axially reciprocating movements of the rollers in directions transverse to the direction of advancing work pieces. In such a case, a cam 26 formed with a cam groove 27 (Fig. 2a) may be mounted on each shaft 18 and cooperating with a pin or cam follower 28 mounted on the machine frame 1 so that shaft 18 and the buff roller 11 mounted thereon is reciprocated in axial direction during rotation of the shaft.

Without further analysis, the foregoing will so fully reveal the gist of the present invention that others can by applying current knowledge readily adapt it for various applications without omitting features that, from the standpoint of prior art, fairly constitute essential characteristics of the generic and specific aspects of this invention, and, therefore, such adaptations should and are intended to be comprehended within the meaning and range of equivalence of the following claims.

What is claimed as new and desired to be secured by Letters Patent is:

1. A machine for polishing surfaces of wood plates and like products comprising, in combination, a base; conveyor means supported by said base for advancing the plates in a plane; a housing supported by said base and having an open side adjacent to and facing the plane in which said plates are advanced; a pair of buff roller means in said housing and being each turnable about an axis substantially parallel to said plane and extending in a direction transverse to the direction in which the plates are advanced; adjustable connecting means operatively connected to said housing and said base for moving said housing toward and away from said plane; and means operatively connected to said base and each of said buff roller means for independently adjusting the distance of each buff roller means axis from said plane.
2. A machine for polishing surfaces of wood plates

and like products comprising, in combination, a base; conveyor means supported by said base for advancing the plates in a plane in one direction; a housing supported by said base and having an open side adjacent to and facing the plane in which said plates are advanced; a pair of buff rollers in said housing and having each an axle substantially parallel to said plane and extending in a direction transverse to the direction in which the plates are advanced; drive means for driving said pair of buff rollers independently from each other at different circumferential speeds, the buff rollers leading in said one direction being driven with a smaller circumferential speed than the other buff roller; adjustable connecting means operatively connected to said housing and said base for moving said housing toward and away from said plane; and means operatively connected to said base and each of said axles for independently adjusting the distance of each axle from said plane.

3. A machine for polishing surfaces of wood plates and like products comprising, in combination, a base; conveyor means supported by said base for advancing the plates in a plane in one direction; a housing supported by said base and having an open side adjacent to and facing the plane in which said plates are advanced; a pair of buff rollers in said housing and having each an axle substantially parallel to said plane and extending in a direction transverse to the direction in which the plates are advanced; drive means for driving said pair of buff rollers independently from each other at different circumferential speeds and for reciprocating said buff rollers in axial direction, the buff rollers leading in said one direction being driven with a smaller circumferential speed than the other buff roller; adjustable connecting means operatively connected to said housing and said base for moving said housing toward and away from said plane; and means operatively connected to said base and each of said axles for independently adjusting the distance of each axle from said plane.

4. A machine for polishing surfaces of wood plates and like products comprising, in combination, a base; conveyor means supported by said base for advancing the plates in a plane; a housing supported by said base and having an open side adjacent to and facing the plane in which said plates are advanced; a pair of buff rollers in said housing and having each an axle substantially parallel to said plane and extending in a direction transverse to the direction in which the plates are advanced; at least one pressure roller means mounted on said housing for rotation about an axis substantially parallel to said axles and adapted to engage the top surface of the wood plates to be polished for holding these plates against said conveyor means; adjustable connecting means operatively connected to said housing and said base for moving said housing toward and away from said plane; and means operatively connected to said base and each of said axles for independently adjusting the distance of each axle from said plane.

5. A machine for polishing surfaces of wood plates and like products comprising, in combination, a base; conveyor means supported by said base for advancing the plates in a plane in one direction; a housing supported by said base and having an open side adjacent to and facing the plane in which said plates are advanced; a pair of buff rollers in said housing and having each an axle substantially parallel to said plane and ex-

tending in a direction transverse to the direction in which the plates are advanced; drive means for driving said pair of buff rollers independently from each other at different circumferential speeds, the buff rollers leading in said one direction being driven with a smaller circumferential speed than the other buff roller, said drive means comprising a pair of motors, each mounted on a plate tiltable, respectively, about axes substantially parallel to said axles and spaced from the center of gravity of said motors, respectively, and being connected to said axles, respectively, by an endless drive element; adjustable connecting means operatively connected to said housing and said base for moving said housing toward and away from said plane; and means operatively connected to said base and each of said axles for independently adjusting the distance of each axle from said plane.

6. A machine for polishing surfaces of wood plates and like products comprising, in combination, a base; conveyor means supported by said base for advancing the plates in a plane; a housing supported by said base and having an open side adjacent to and facing the plane in which said plates are advanced; a pair of buff rollers in said housing and having each an axle substantially parallel to said plane and extending in a direction transverse to the direction in which the plates are advanced; means in said housing adjacent said buff rollers for applying polishing material thereto; adjustable connecting means operatively connected to said housing and said base for moving said housing toward and away from said plane; and means operatively connected to said base and each of said axles for independently adjusting the distance of each axle from said plane.

7. A machine for polishing surfaces of wood plates and like products comprising, in combination, a base; conveyor means supported by said base for advancing the plates in a plane; a housing supported by said base and having an open side adjacent to and facing the plane in which said plates are advanced; a pair of buff rollers in said housing and having each an axle substantially parallel to said plane and extending in a direction transverse to the direction in which the plates are advanced; adjustable connecting means operatively connected to said housing and said base for moving said housing toward and away from said plane; and means for independently adjusting the distance of each axle from said plane, said means comprising a pair of arms for each of said buff rollers, said arms being pivotally connected at one end thereof to said housing for turning movement about an axis substantially parallel to the axle of the respective buff roller and turnably carrying at the other end thereof the axle of the respective buff roller, said one end of one arm of each pair being also connected to said housing for tilting movement about an axis substantially normal to said axle, and means for tilting said arms of each pair through the same angle about said axis parallel to said axle.
